UNITED STATES PATENT OFFICE.

CLARENCE B. FOWLER, OF NEW YORK, N. Y., ASSIGNOR TO WESTERN ELECTRIC COMPANY, INCORPORATED, OF NEW YORK, N. Y., A CORPORATION OF NEW YORK.

CONNECTING CIRCUITS.

Application filed August 29, 1923. Serial No. 659,877.

To all whom it may concern:

Be it known that I, CLARENCE B. FOWLER, a citizen of the United States of America, residing at New York, in the county of New York and State of New York, have invented 5 certain new and useful Improvements in Connecting Circuits, of which the following is a full, clear, concise, and exact description.

10 This invention relates to circuits for use in telephone exchange systems for interconnecting subscribers' lines, and more particularly, to connecting circuits for use in extending connections from subscribers' lines 15 terminating in a plurality of connecting terminals.

Among the objects of the invention is to simplify and improve the circuit arrangements of such connecting circuits so that 20 only one connecting circuit can be operatively connected to a calling line at a time.

In accordance with one feature of the invention there is provided a testing circuit common to a plurality of connecting circuits having a pair of polarized relays, one 25 of which operates if an operator connects a connecting circuit to an idle line to permit the connection of an operator's telephone set to the line, and the other of which operates if a busy line is seized by the operator to prevent the connection of the operator's telephone set to the line.

Another feature of the invention resides in the provision of signaling apparatus in 30 a circuit arrangement of this character for indicating to the operator the busy condition of the seized line.

In the drawings,

Fig. 1 shows a calling station A and a 35 called station B with associated line circuits, one of a plurality of connecting or link circuits C, which may be used to interconnect such stations, and an operator's telephone set and testing circuit O common to a plurality of the link circuits.

Fig. 2 shows diagrammatically an unbalanced Wheatstone bridge circuit in which the controlling relays of the testing circuit are connected when a second link circuit 40 is connected with a line with which another link circuit is already connected.

Each of the stations A and B is shown 45 terminating at the central office in a plurality of answering jacks and a multiple jack. Each answering jack has a signal-

ing device associated therewith. The answering jacks and their associated line lamps for a station terminate at different operators' positions. Multiple jacks, only one of which is shown in the drawing, may appear 60 at each operator's position.

In the following detailed description it will be assumed that a subscriber at the station A is the calling subscriber and that a subscriber at station B is the called subscriber.

Upon initiating a call, the subscriber at station A removes the receiver from the switchhook and establishes an energizing circuit for line relay 3 which operates. Relay 3, in operating, completes a circuit extending from grounded battery through the filaments of the line lamps 8 and 9, which lamps are located in front of different operators at the central office, any one of which 70 operators may answer the call. The lamps are illuminated notifying all the operators that a call is awaiting attention.

It will be assumed that at this time the operator at the position at which lamp 8 80 is located is free to handle the incoming call. This operator, therefore, inserts the plug 11 associated with the cord circuit C into jack 12 located at her position and associated with the calling subscriber's line. 85

Upon the insertion of plug 11 into jack 12, a starting relay 20 common to the link circuits of the operator's position, operates over a circuit from ground, through the winding of cut-off relay 4, sleeve contacts 90 of jack 12 and plug 11, winding and contact 64 of relay 14, contact 65 of relay 33, conductor 75, contact 66 of relay 31, contact 67 of relay 32, winding of relay 20, contact 68 of relay 35 and contact 69 of relay 31 to grounded battery. Relays 4 and 14 included in this circuit do not receive sufficient current at this time to operate. Relay 20 in operating causes the operation of relay 32. Relay 32 in attracting its inner 100 left hand armature, opens at contact 67 a shunt path normally connected around the polarized relays 30 and 40, connects ground through contact 72 of relay 32 between resistance 19 and relay 20, and connects grounded battery through resistance 18 and contact 73 of relay 32 between relay 40 and resistance 19.

With relay 32 operated and with ground and grounded battery connected to resistances 19 and 18, as described, 110

a potentiometer circuit arrangement is formed. The closure of contact 72 of relay 32 completes a circuit including contact 68 of relay 35 and contact 69 of relay 31 for holding relay 20 operated.

Since the line has been assumed to be free, current will now flow through relays 30 and 40 over conductor 75 in a direction such as to operate relay 30. Relay 40 does not operate at this time because the current flow through its winding is not in the proper direction. This path may be traced as follows: from ground, through the winding of cut-off relay 4, sleeve contacts of plug 11 and jack 12, winding and contact 64 of relay 14, contact 65 of relay 33, conductor 75, contact 66 of relay 69, windings of relays 30 and 40, contact 73 of relay 32 and thence through one arm of the potentiometer circuit including resistance 18 to grounded battery. It will be noted that current also flows at this time through resistance 18 and resistance 19 (forming the other arm of the potentiometer circuit) to ground but this current flow is ineffectual.

Relay 30, in operating, completes a circuit for relay 31 over a path from grounded battery through the contact of relay 30, right hand winding of relay 31, and right-hand contact of relay 32 to ground. Relay 31 thereupon operates and locks over a path extending from grounded battery, through the right hand alternate contact and winding of relay 31 and right hand contact of relay 32 to ground. Relay 31, in operating, opens at its contact 69, the energizing circuit for relay 20, whereupon relay 20 releases, which in turn releases relay 32. Relay 31, in operating, also opens at its contact 66 the circuit for relay 30, whereupon relay 30 releases. In attracting its left hand armature, relay 31 connects its left hand winding and resistance 17 in multiple to the conductor 75. This circuit being established before the release of relay 32, relay 31 remains operated after the release of relay 32.

The connection of grounded battery through the left hand winding of relay 31 and resistance 17 in parallel increases the current flow over the conductor 75 sufficiently to permit the operation of the sleeve relay 14 and the cut-off relay 4. Relay 14, in operating, locks over a path extending from ground, through the winding of cut-off relay 4, sleeve contacts of jack 12 and plug 11, winding and contact 61 of relay 14, and lamp 55 to grounded battery. Relay 14, in operating, opens the circuit extending to conductor 75, whereupon relay 31 releases restoring the testing equipment including relay 31 to normal position. When cut-off relay 4 operated it disconnected the line relay 3 from the calling line and extinguished the multiple line lamp.

When relay 14 operated, a circuit was

completed for supervisory relay 13. Relay 13 in operating, connects a low resistance 22 in shunt at supervisory lamp 55 thereby extinguishing it.

The operator then after actuating listening key 42 to connect her receiver 81 and transmitter 90 in operative relationship with the cord circuit, ascertains from the calling subscriber the nature of the call, and upon learning that the subscriber at station B is desired, tests the called line in the well known manner and, if it is idle, inserts the calling plug 47 into the multiple jack 48 associated with the station B. The operator may then restore key 42 to normal.

When plug 47 is inserted into jack 48, supervisory lamp 49 lights and relays 33 and 56 operate over a circuit from grounded battery, through the lamp 49, winding of relay 33, sleeve contacts of plug 47 and jack 48 and winding of cut-off relay 56 to ground. The operation of cut-off relay 56 disconnects line relay 53 from the called station B. Relay 33, in operating, transfers the tip of the calling plug from connection with the busy test lead 76 to connection with the upper right hand winding of the repeating coil 15, closes a short circuit through its contact 82 around the make-before-break contacts of relay 14 and disconnects at its contacts 65, the start conductor 75 from the answering end of the cord. The start conductor is now open at two points, namely at contact 65 and at contact 61 so that the release of either of the sleeve relays alone cannot connect the start conductor 75 to the sleeve of the answering plug.

The operator then actuates the ringing key 43 to signal the called station B. After signaling the called station, the operator restores key 43 to normal position.

When the called substation responds, supervisory relay 58 operates to connect resistance 52 in shunt of supervisory lamp 49 to extinguish it.

The calling station and the called substation B may now converse with each other, and upon completion of conversation and restoration of their respective receivers to the switchhooks, supervisory relays 13 and 58 deenergize, causing their associated lamps 55 and 49, respectively, to light, indicating to the operator that conversation has ceased. The operator, noting the lighted condition of the supervisory lamps, may withdraw plugs 11 and 47 from their associated jacks, whereupon all of the apparatus is restored to normal.

Having described in detail the establishment of a connection between a subscriber at station A and a subscriber at station B, it will now be assumed that the operator at which jack 12 and its associated lamp 8 appears, has answered a call from the subscriber at station A and that an operator at

the position at which lamp 9 is located attempts to handle the call upon noting the illumination of lamp 9. It is to be understood that the operator at such position attempts to handle an incoming call immediately after the first operator has answered a call, otherwise the lamp 9 would have been extinguished upon the insertion of plug 11 into jack 12.

10 The second operator, having a cord and associated test and operator's circuit identical with the one shown in the drawing, inserts the plug 11 thereof into jack 50. The sleeve of jack 50 being multiplied with that 15 of jack 12, now has a busy potential connected thereto owing to the insertion of plug 11 of the original cord into jack 12 by the first operator. The potential on the sleeve of jack 12 has been provided from the battery 20 associated with the sleeve of the plug of the original cord.

Upon inserting plug 11 of the second cord into jack 50, an energizing circuit is established for relay 20 over a path extending 25 from ground, through the winding of cut-off relay 4, sleeve of jack 50 and sleeve of the second cord 11, winding and contact 64 of relay 14 of the second cord, contact 65 of relay 33 of the second cord, contact 66 of relay 31 of the second cord, contact 67 of relay 32 of the second cord, winding of relay 20 of the second cord, contact 68 of relay 35 of the second cord and contact 69 of relay 31 of the second cord to grounded battery. Another path for current through the 30 winding of relay 4 to ground extends through the sleeves of jack 12 and plug 11 and winding of relay 14 to battery potential, but relay 20 of the second cord is of the sensitive type and operates in the parallel branch 35 to battery extending to the second cord. Relay 20 of the second cord in operating causes the operation of relay 32 which closes at its contact 72 the circuit previously traced 40 for holding relay 20 operated. Due to the fact that a plug at another operator's position has been previously inserted into a multiple of the jack 50, the current flowing through the polarized relays 30 and 40 is in 45 a direction opposite to that which it was when the line was idle and is in such a direction as to cause the operation of polarized relay 40 only. The reason that the current flows in a reversed direction at this time 50 is due to the fact that an unbalanced Wheatstone bridge arrangement is formed in which the sleeve circuit of the first connected link circuit and resistance 18 associated with the second link circuit form two adjacent arms 55 with battery connected between them, and resistance 19 of the second link circuit and cut-off relay 4 form the two other adjacent arms with ground connected between them, and in which relays 30, 40 and 14 of the 60 second link circuit form the bridge arm. 65

This unbalanced Wheatstone bridge circuit is shown in Fig. 2, wherein the apparatus associated with the second connected link circuit is indicated by reference characters with primes and the apparatus associated with the line and the first connected link circuit is indicated by reference characters without primes. It has been found that with the values of resistance indicated hereinafter this current reversal exists not only 70 when a second operator plugs in a calling line but also when a plurality of operators plug in a calling line after the first operator has obtained the connection.

The operation of polarized relay 40 associated with the second connected link circuit causes the operation of relay 35 and establishes a holding circuit for relay 32 through the right hand winding thereof. Relay 35 in operating releases relay 20 and 80 opens contacts in the leads from the operator's telephone set extending to the listening key 42 of the second connected link circuit and the listening keys of the other link circuits at the same operator's position. The 85 closing of the alternate contacts of relay 35 connects a source of tone supply 80, to the receiver 81 to indicate to the operator the busy condition of the calling line or the fact that the call has already been answered by 90 another operator. The resistance of the common apparatus of the test circuit is at this time of such a value as to prevent the operation of marginal relay 14 of the second 95 link circuit and the operator's telephone set 100 therefor is barred.

The operator, noting the tone signal, removes the plug 11 at the second operator's position from jack 50, whereupon relay 40 releases. Relay 40, retracting its armature, 105 opens the holding circuit for relay 32, which then releases. Relay 35 is of the slow to release type and retracts its armature an interval after its energizing circuit is opened 110 at the contacts of relay 40.

According to one way in which the invention has been practiced all operators except the one first to answer a call are barred from the connection when a 24 volt battery is employed and the resistances and relays 115 employed in association with the testing circuit have the values set forth below.

Relay 4, 84 ohms; relay 14, 90 ohms; relay 30, 42 ohms; relay 40, 42 ohms; relay 20, 1800 ohms; relay 31, 250 ohms for the 120 left hand winding.

Resistance 19, 15 ohms; resistance 17, 170 ohms; resistance 18, 125 ohms.

Obviously, other resistance values for the apparatus involved in the test and line circuits may be employed.

The invention claimed is:

1. The combination with a number of telephone lines extending from substations to multiple terminals at a central office, of a 130

plurality of link circuits each having a manual connecting terminal, telephonic apparatus common to said link circuits, blocking mechanism for rendering said telephonic apparatus inert, means common to said link circuits for controlling said blocking mechanism, and a circuit completed for said means in response to the connection of one of said manual connecting terminals to one of the terminals of a busy line.

2. The combination with a number of telephone lines extending from substations to multiple terminals at a central office, of a plurality of link circuits each having an answering and calling plug, telephonic apparatus common to said link circuits, blocking mechanism for rendering said telephonic apparatus inert, means common to said link circuits for controlling said blocking mechanism, and a circuit completed for said means as one of said answering plugs engages the terminal of a busy line.

3. In a telephone system, a calling line, an operator's telephone set, and a cord circuit for connection with said line provided with testing apparatus including a pair of polarized relays, one of said relays operating if the line is idle to permit the connection of the operator's set to the cord circuit, and the other of said relays operating if the line is busy to prevent the connection of the operator's set to the cord circuit.

4. In a telephone system, a calling line, an operator's telephone set, and a cord circuit for connection with said line provided with testing apparatus including a pair of polarized relays, one of said relays operating if the line is idle to permit the connection of the operator's set to the cord circuit and the other of said relays operating if the line

is busy to prevent the connection of the operator's set to the cord circuit and to connect a tone to the operator's telephone set.

5. In a telephone system, a calling line terminating in a connecting terminal, a cord circuit for connection therewith, an operator's telephone equipment for said cord circuit, a testing circuit associated with said cord circuit including a pair of polarized relays, a source of current, and circuit connections arranged so that current from said source flows in a direction to operate one of said relays, if the line seized is idle, to permit the connection of the operator's telephone equipment to the calling line, and in another direction to operate another of said relays, if the line seized is busy, to prevent the connection of the operator's equipment to the calling line.

6. In a telephone system, a calling line terminating in a plurality of connecting terminals, a cord circuit for connection with one of said terminals, an operator's telephone equipment for said cord circuit, a testing circuit associated with said cord circuit including a pair of polarized relays, a source of current, and circuit connections arranged so that current from said source flows in a direction to operate one of said relays, if the line seized is idle, to permit the connection of the operator's telephone equipment to the calling line, and in another direction to operate another of said relays, if the line seized is busy, to prevent the connection of the operator's equipment to the calling line and to connect a source of tone to the operator's equipment.

In witness whereof, I hereunto subscribe my name this 23 day of August A. D., 1923.

CLARENCE B. FOWLER.
